(57) **CLAIM**

The ornamental design for a recovery tank for carpet extractor, as shown and described.

DESCRIPTION

FIG. 1 is a perspective view of a recovery tank for carpet extractor showing our new design;

FIG. 2 is a perspective view thereof;

FIG. 3 is a left side elevational view thereof;

FIG. 4 is a front elevational view thereof;

FIG. 5 is a right side elevational view thereof;

FIG. 6 is a rear elevational view thereof;

FIG. 7 is a top plan view thereof;

FIG. 8 is a bottom plan view thereof; and,

FIG. 9 is a perspective view of a base of the carpet extractor in an open position to allow the recovery tank to be removed therefrom.

While portions of the recovery tank are not visible in FIG. 1, the entire recovery tank is shown in FIG. 2.

The carpet extractor parts shown in broken lines in FIGS. 1 and 9 are shown for illustrative purposes only and form no part of the claimed design.
